CLAIM

The ornamental design for a shoe, as shown and described.

DESCRIPTION

FIG. 1 is a front, right-side perspective view of our new design.

FIG. 2 is a right-side view thereof.

FIG. 3 is a left-side view thereof.

FIG. 4 is a top view thereof.

FIG. 5 is a bottom view thereof.

FIG. 6 is a front view thereof; and, FIG. 7 is a rear view thereof.

The broken lines consisting of dot-dash lines in the drawings are boundary lines that show that the claimed design extends to the boundary line but does not include the boundary line. The remaining portions of the shoe rendered in short broken lines form no part of the claim.
